US00D611326S

(12) **United States Design Patent**
Alaniz et al.

(10) **Patent No.:** US D611,326 S
(45) **Date of Patent:** ** Mar. 9, 2010

(54) **RACEWAY FOR CABLE MANAGEMENT**

(75) Inventors: **Daniel Alaniz**, Austin, TX (US); **D. Brian Donowho**, Austin, TX (US); **James I. Lawrence**, Georgetown, TX (US); **Richard E. Lewis, II**, Austin, TX (US); **Scott Alexander Smith**, Lago Vista, TX (US); **Joshua James Young**, Austin, TX (US)

(73) Assignee: **Chatsworth Products, Inc.**, Westlake Village, CA (US)

(**) Term: **14 Years**

(21) Appl. No.: **29/299,950**

(22) Filed: **Jan. 7, 2008**

(51) LOC (9) Cl. **08-08**

(52) U.S. Cl. **D8/356; D13/155**

(57) **CLAIM**

The ornamental design for a raceway for cable management, as shown.

DESCRIPTION

FIG. 1 is an isometric view of the design for a raceway for cable management in accordance with a preferred embodiment of the present invention;

FIG. 2 is a front view of the raceway for cable management of FIG. 1;

FIG. 3 is a left view of the raceway for cable management of FIG. 1;

FIG. 4 is a right view of the raceway for cable management of FIG. 1;

FIG. 5 is a rear view of the raceway for cable management of FIG. 1; and,

FIG. 6 is a top plan view of the raceway for cable management of FIG. 1.

Portions of the design shown in broken lines form no part of the claimed design.
